ATTORNEYS.

UNITED STATES PATENT OFFICE.

HENRY B. BOHR, OF CINCINNATI, OHIO, ASSIGNOR TO THE JULIAN & KOKENGE COMPANY, OF CINCINNATI, OHIO, A CORPORATION OF OHIO.

SHOE.

Application filed February 11, 1921. Serial No. 444,242.

To all whom it may concern:

Be it known that I, HENRY B. BOHR, a citizen of the United States, and a resident of the city of Cincinnati, in the county of Hamilton and State of Ohio, have invented certain new and useful Improvements in Shoes, of which the following is a full, clear, and exact description, reference being had to the drawings forming part of this specification.

My invention relates to shoes having the function of assisting the natural or physiological action of the human foot.

Without in detail describing the anatomical structure of the human foot, it may be noted that it is a resilient structure of bones, ligaments, muscles, tendons, and fleshy pads, which support the human body and provide for the locomotion thereof in connection with the leg and its muscles.

The heel bone or "os calcis" receives the chief weight of the body, and is protected by a pad of fleshy nature, and hard tough skin. The toes and their bones called the phalanges, are employed in bodily locomotion, these bones being connected to a series of bones called the metatarsal bones, one for each phalanx.

The metatarsal bones are somewhat arched in a transverse direction of the foot, and part of the weight of the body is borne by these bones, with the points of contact being substantially on the bones at the inner and outer sides of the foot; one from the great toe and one from the little toe. Pads of flesh protect these points of contact.

Between the metatarsal bones and the heel are a series of bones forming a long arch longitudinally of the foot. At the inside of the foot, this structure slopes up sharply in a further arch, and the astragalus bone serves as the connection from the lower bone of the leg (tibia) to the bones of the foot.

The ligaments, muscles, and fleshy structure of the foot serve to make of the arched bone foundation a resilient padded base for the body with flexible toes, and a joint for the entire structure at the ankle.

It may be seen from this non-technical description, that the weakness of the foot is likely to take place at the arched portions and the interconnecting ligaments and it is

the object of my invention to provide a shoe which closely follows the arched formation of the foot, so as to provide a brace for this portion thereof.

Another object of my invention is to provide for this support by building up a metallic structure on the outer sole of the shoe and a resilient structure between this metallic portion and the inner sole of the shoe, this resilient structure being such as to fit the base of a natural human foot from the metatarsals to the back of the heel or calcis bone.

Another object of my invention is to form within the shoe a metatarsal as well as a longitudinal arch, this longitudinal arch having the transverse components of the normal long arch of the foot.

Generally speaking, I desire that the conformation of the outer sole be substantially that of the inside of the inner sole, although this is not essential, and I form my shoe over a last which is substantially conformed at the base to correspond to the base of a normal human foot.

Accordingly, as it will be pointed out, I provide a shoe which while following the true external conformation of the human foot, and bracing the foot at the arch with a metallic member, still provides a tread base for the foot which is perceptibly resilient, and permits the muscular structure of the foot to perform its normal function, giving the body a resilient support.

Furthermore, as will be noted, I may make my shoe with a heel of the height which will lift the heel bone to the natural position of the relaxed human foot. If one lifts the leg and permits the foot to droop naturally with all muscles relaxed, it will assume a position with the heel well elevated. This drooping or relaxed position of the foot, in my novel shoes may be maintained by lifting the heel to the height required to bring this result.

The various objects above noted, I accomplish by that certain construction and arrangement of parts to be hereinafter more specifically pointed out and claimed.

In the drawings,

Figure 1 is a side elevation of a shoe made in accordance with my invention, the sole

parts being shown in central longitudinal section.

Figure 2 is a bottom plan view of a welt shoe in process of construction according to my invention.

Figure 3 is a section on the line 3—3 of Figure 1.

Figure 4 is a view similar to Figure 2 with the metal shank piece and filler not yet attached.

Figure 5 is a perspective view of one form of metal shank piece employed in my invention.

Figure 6 is a like view of the preferred form of resilient element.

Figure 7 is a bottom perspective view of the anatomical structure of the human foot, with the bones named, and the points of support of the body indicated by the word "Contact."

Figure 8 is a bottom plan view of a last, preferably employed with my invention, showing in dotted lines the bony structure of the foot.

I am aware that it is not novel to insert a metal shank piece in the arch portions of a shoe, and that it is old to employ a last in making shoes which conforms at the base with the structure of the foot. But to my mind each of these old systems of manufacture has resulted in a failure to fully provide for foot support and comfort, since, so far as I am advised, no one has provided a combination metal shank shoe, strongly supported by the shank, and yet made on a last which responds to the exact shape of the arch portions of the human foot. My invention not only provides for such a combination, but it also gives a resilient tread base for the feet.

Referring first to Figures 7 and 8, it will be noted without particular description that Figure 7 shows thereon the various essential bones of the human foot, the view being taken from the bottom of the foot. Figure 8 shows a last 1, having a toe 2, and heel 2a. These two portions of the last will be subject to change dependent upon the style shoe which it is desired to produce. At the shank 3, the last is curved longitudinally and transversely to correspond to the base of the human foot, and at the forward end of the shank, as shown at 4, the portions between the shank and toe are likewise formed to correspond with the metatarsal foot structure.

In making up my shoe, I place the insole 5 on the last, (the process illustrated being the welt process) and then cement thereto a heel seat 6, of resilient nature, such as a piece of rubber, cut to conform to the heel of the insole. I then pull over and secure the upper 7, and by the usual process of inseaming, secure the welts 8, and the upper to the insole lip 9.

Although any sort of resilient material would suffice, I prefer that the piece of rubber 10, cut with transverse curfs 11, be provided, which fits the insole between the lip portions thereof, extending from the ball 70 of the foot to the upper at the heel. This piece is cemented down in place and is formed with the central portions thereof thicker than the edges, this being so arranged because of the transversely arched 75 shape of the metal shank piece.

Preferably after the piece 10 is placed on the insole, the cork-like filling 12 is placed between the raised portions of the insole caused by the lip, with the welt and upper 80 stitched thereto, and then the metal shank piece 13 is laid over the rubber or other resilient piece 10, and preferably tacked thereto.

This metal shank 13 is rigid and substantially non-resilient and is formed in an arch longitudinally and transversely, this being the strongest possible construction. It extends preferably for the full width of the piece 10, and from the point just be- 90 hind the metatarsal tread portions of the foot, to the middle of the heel.

The construction of the shoe is then completed as in the ordinary welt shoe process, with the result of bringing the insole tightly 95 up against the base of the last, and conforming it exactly thereto, and bringing the sole of the shoe firmly over the assembled portions on the last.

The shape of the outer sole will be gov- 100 erned by the shape of material placed between the last and said outersole, with the metal shank piece serving as the guiding feature.

Thus to change the shape of the outer sole, the metal shank piece may be made up in the desired shape for the shank portions of the sole, the filler piece 10 shaped to fill the space between the shank piece and the shank of the last, and the outer-sole formed 110 to the last as in the usual welt shoe process.

In providing a heel for the shoe, I prefer to provide a heel 14, which will result in a natural relaxed position of the foot, although this is not at all essential to the 115 advantageous nature of my invention. As noted, this relaxed position of the foot is that which the foot will naturally take when elevated from the ground, with the normal muscular structure entirely relaxed permitting the toe to fall.

It is not necessary to describe in detail the conformation of the shoe on the inside, since this conforms to the shape of the last and of the normal human foot. As to the 125 outer sole, among other things it will normally take a curved line throughout the shank, both transversely and longitudinally, and at the ball or metatarsal portion of the foot will present a curve extending for- 130

wardly at the inside of the foot, but, of course, without any depression at the metatarsal arch. This curve presents to the eye a much superior appearance to the toe portion of the ordinary shoe of today.

So long as the shaping to the shank and metatarsal portions are maintained for the shoe, the toe formation may be varied to suit the fashions, without substantially affecting the re-action on the foot, provided sufficient toe room is left, since instead of a few bones supporting the foot, the pressure outside of the heel is taken by substantially all of the bones.

15 The effect of the rubber at the heel is to take the place of the unsightly rubber heels, while preserving in the main all of their advantageous functions. The effect of the rubber throughout the shank portions of the 20 foot, and as a filler between the last and the sole at the metatarsal portions, is to provide a natural cushion for the foot, which does away with the rigid feeling of a stiff metal shank, and eliminates the blow against 25 the bones and muscular structure, which

would be otherwise imparted during use by the wearer.

Having thus described my invention, what I claim as new, and desire to secure by Letters Patent, is:—

1. In a shoe, an insole shaped to provide a support for the structure of the foot intermediate the normal tread portions thereof, an outsole, and a filler between the outsole and the insole having a non-resilient metallic portion, and a resilient portion lying between the outsole and the insole. 35

2. In a shoe, an insole shaped to provide a support for the structure of the foot intermediate the normal tread portions thereof, an outsole, and a filler between the outsole and the insole having a non-resilient metallic portion, and a resilient portion, both lying between the insole and the outsole, and the resilient portion lying at least 40 in part between the metallic portion and the insole to serve as a cushioning pad for the said metallic portion. 45

HENRY B. BOHR.
